Primary Examiner—Carol Rademaker(74) *Attorney, Agent, or Firm*—Jaekle Fleischmann & Mugel, LLP(57) **CLAIM**

The ornamental design for a bottle, as shown and described.

DESCRIPTION

FIG. 1 is a front perspective view of our new ornamental design for a bottle according to the present invention;

FIG. 2 is a top view of the ornamental design for a bottle shown in FIG. 1;

FIG. 3 is a front view of the ornamental design for a bottle shown in FIG. 1;

FIG. 4 is a right side view of the ornamental design for a bottle shown in FIG. 1;

FIG. 5 is a rear view of the ornamental design for a bottle shown in FIG. 1;

FIG. 6 is a left side view of the ornamental design for a bottle shown in FIG. 1; and,

FIG. 7 is a bottom view of the ornamental design for a bottle shown in FIG. 1.

The broken lines shown on the bottom in the FIG. 7 drawing view are for environmental purposes only and form no part of the claimed design.
